(57) **CLAIM**

The ornamental design for a display module, as shown and described.

DESCRIPTION

FIG. 1 is a perspective view of a first embodiment of a display module;

FIG. 2 is a front view of the first embodiment;

FIG. 3 is a rear view of the first embodiment;

FIG. 4 is a left-side view of the first embodiment;

FIG. 5 is a right-side view of the first embodiment;

FIG. 6 is a top view of the first embodiment;

FIG. 7 is a bottom view of the first embodiment;

FIG. 8 is an enlarged view of the area of FIG. 2 designated by the dot-dash line;

FIG. 9 is a perspective view of a second embodiment of a display module;

FIG. 10 is a front view of the second embodiment;

FIG. 11 is a rear view of the second embodiment;

FIG. 12 is a left-side view of the second embodiment;

FIG. 13 is a right-side view of the second embodiment;

FIG. 14 is a top view of the second embodiment;

FIG. 15 is a bottom view of the second embodiment; and,

FIG. 16 is an enlarged view of the area of FIG. 10 designated by the dot-dash line.

The broken lines shown in the drawings illustrate portions of the display module that form no part of the claimed design. The dot-dash lines are imaginary lines that are included for reference purposes only to identify partially enlarged views; the dot-dash lines form no part of the claimed design.
